UNITED STATES PATENT OFFICE.

MELBERN B. BULLA, OF EL PASO, TEXAS.

AUTOMATIC TRAIN-STOP.

1,267,179.

Specification of Letters Patent. Patented May 21, 1918.

Application filed December 14, 1916. Serial No. 136,891.

To all whom it may concern:

Be it known that I, MELBERN B. BULLA, a citizen of the United States, and a resident of El Paso, in the county of El Paso and

5 State of Texas, have invented a new and Improved Automatic Train-Stop, of which the following is a full, clear, and exact description.

This invention relates to automatic train stops of the general type covered by Letters Patent of the United States, issued to me on November 7, 1916, No. 1,203,970.

Among the objects of the present improvement is to simplify the construction where- 15 by fewer magnets and changeable switches are necessary.

Another object of the invention is to provide automatic train control mechanism including a normally closed circuit, the break- 20 age or disarrangement of any part of which will insure the stopping of the train.

A still further object of the invention is to provide a means whereby, even though the automatic stopping mechanism is con- 25 trolled by the normally closed circuit, yet the engine driver is enabled to pass a danger point if required to do so under orders without initiating the action of the automatic stopping mechanism.

30 With the foregoing and other objects in view the invention consists in the arrangement and combination of parts hereinafter described and claimed, and while the invention is not restricted to the exact details of 35 construction disclosed or suggested herein, still for the purpose of illustrating a practical embodiment thereof reference is had to the accompanying drawings, in which like reference characters designate the same parts 40 in the several views, and in which—

The figure is a side elevation of my improvement, showing the devices carried in a casing in the locomotive cab and indicating diagrammatically the electric wiring and 45 contact devices.

Referring now to the drawing and to lay a substantial basis for the description of the novel features, I will refer briefly to the conventional parts, among which are indi- 50 cated a casing 10, upwardly through which is extended an air pipe 11 in communication at its lower end with the train line (not shown) and in communication at its upper end with the atmosphere. The pipe 11 is 55 normally held closed by means of a trip valve 12 adapted to be operated by a lever

13 pivoted at 14 and having a rod 15 connected to the piston of a motor cylinder 16, similar to the device disclosed in my previous patent above mentioned. 60

17 indicates a branch pipe normally charged with compressed air either from the train line or the pipe 11, such pressure, however, being retained by means of a valve 18 held normally closed against the force of a 65 spring 19. This spring in connection with the force of gravity, tends to open the valve 18 so as to permit the compressed air in the pipe 17 to pass through the pipe 20 to the motor cylinder 16 and at the same time 70 through a branch pipe 21 to actuate the throttle lever or any other part desired to be operated simultaneously with the setting of the brakes. 22 indicates a pipe communicating with the atmosphere and normally 75 communicating with the pipe 20 so that any leakage of air through the valve 18 will be dissipated rather than actuate the piston in the cylinder 16. The opening of the valve 18, however, serves to close the outlet pipe 22. 80

23 indicates a magnet whose armature 24 is connected to the valve 18 by means of a link 25, and, acting as a lever of the third class, serves when the magnet is energized to hold the valve in its normal closed position. The moment, however, that this magnet is deenergized, the spring 19 snaps the valve 18 open, overcoming thereby any residual magnetism in the core of the magnet. 85

26 represents any suitable battery carried 90 in any convenient place on the locomotive, the energy from which is depended upon to normally energize the magnet 23 and hold the valve closed. The course of such energy from the battery is through a wire 27, a shoe 95 28, and wire 29 to and through a pilot magnet 30, wire 45, armature 44, and contact 46, thence through a wire 31 to the magnet 23, thence through a wire 32, contact piece 33 and wire 34 back to the battery. 100

I provide a brush 35 along the track adapted to be struck by the shoe when the danger signal is set and the train is run past the danger point. This brush is grounded as indicated at 36, and hence when 105 the shoe strikes the brush, the energy from the battery instead of passing through the magnets will pass immediately to the ground, thereby deenergizing both magnets. The circuit at such time will be as follows: 110 from the battery through wire 27, the shoe 28, brush 35 and the ground 36 on one side

and on the other side, the wire 34, contact piece 33, switch blade 37, contact piece 38 and wire 39 to the ground at 40. This breaking of the circuit through the magnet 23 allows the spring 19 to open the valve 18, admitting compressed air from the pipe 17 to the motor cylinder 16 which opens the main valve at 12, causing the application of the brakes. A record of this opening of the valve will be made at the counter 41 through the lever 18 and link 42. The magnets remain deenergized until the system is restored which is accomplished by the oscillation of the lever 43 to which the switch blade 37 is connected. This action is performed by the engineer by hand. It is to be noted that the armature 44 of the magnet 30 acts as a switch blade between the wire 45 and the contact point 46, from which the wire 31 leads to the other magnet. The wire 45 is normally idle, being connected to the contact piece 47 adjacent to another contact 48 having connection through the wire 49 with the battery line 34. A spring 50 connected to the armature 44 tends to throw the armature away from the magnet and the contact 46. To restore the magnet armatures to their normal position, the switch blade 37 is swung to the dotted line position bridging the gap between the contact pieces 47 and 48, at which time the energy from the battery will pass through the magnet 30 as follows: from the battery to the wire 27, shoe 28, and wire 29 on one side and wires 34 and 49, contact piece 48, blade 37, contact piece 47, and wire 45 on the other side. As soon, therefore, as the magnet 30 is reenergized in this manner, the lever 43 will be withdrawn from the contacts 47 and 48, and the pilot magnet 30 will again bring the valve magnet 23 into circuit as follows: battery 26, wire 27, shoe 28, wire 29, magnet 30, wire 45, armature 44, contact 46, wire 31, magnet 23, and wires 32 and 34.

If the engineer is authorized to pass a danger point without stopping the train, he may do so by withdrawing the switch blade 37 out of its normal position, so as not to bridge either pair of contacts, such action being recorded at the counter 51. The ground circuit at this time will be broken at 38, and hence even though the shoe should strike the brush 35, the normal condition of the magnets will not be disturbed. 55

I claim:

1. In an automatic train stop, the combination with a brake air line, a valve normally closing the same, a fluid pressure motor connected to the valve for opening the same and means controlling the delivery of pressure fluid to the motor including a normally closed valve, of a source of energy, a plurality of electromagnets normally arranged in series in circuit with said source of energy, one of said magnets having an armature connected to the latter mentioned valve holding the same closed against the force of means tending to open it, means to cause said magnets to be deenergized 70 simultaneously when a danger point is passed, and means under the control of the engine driver to reenergize the magnets, one in advance of the other to restore the parts to normal running position. 75

2. In an automatic train stop, the combination with a train air line and means to control the delivery of air therefrom for stopping the train, of electromagnetic means to control the air control means, said electromagnetic means including a plurality of electromagnets, a battery common to both of said magnets, connections between the magnets and the battery causing both magnets to be normally energized in running 85 position, means to cause the simultaneous deenergization of both magnets when a danger point is passed, means between one of the magnets and the air control means to prevent the flow of air when the magnets are 90 energized, means independent of the latter mentioned magnet to reenergize the other magnet, and means between the magnets serving to cause the one magnet to be reenergized before the other to restore the 95 parts to normal position. 96

MELBERN B. BULLA.
